UNITED STATES PATENT OFFICE.

WILLIAM AAB, OF NEW ULM, MINNESOTA, ASSIGNOR OF ONE-HALF TO WILLIAM F. LAUDENSCHLAGER, OF NEW ULM, MINNESOTA.

TRANSFER MECHANISM FOR CARRIER SYSTEMS.

933,354.

Specification of Letters Patent.

Patented Sept. 7, 1909.

Application filed September 16, 1908. Serial No. 453,318.

To all whom it may concern:

Be it known that I, WILLIAM AAB, a citizen of the United States, residing at New Ulm, in the county of Brown and State of Minnesota, have invented certain new and useful Improvements in Improved Transfer Mechanism for Carrier Systems; and I do hereby declare the following to be a full, clear, and exact description of the invention, such as will enable others skilled in the art to which it appertains to make and use the same.

My invention has for its object to provide an improved transfer mechanism for carrier systems, and to this end, it consists of the novel devices and combinations of devices hereinafter described and defined in the claims.

This improved transfer mechanism is adapted for use in connection with carrier systems wherein there is a main or primary carrier and one or more branch or secondary carriers arranged at an approximately right angle thereto; and especially, said transfer mechanism is adapted for use where the carriers above noted involve laterally spaced endless carrier belts or cables and coöperating, guiding and driving wheels.

Carrier systems of this character are now in general use for a great many different purposes. For instance, they are found very serviceable in brick yards to convey pallet boards loaded with bricks from the press along the main or primary carrier to one or the other of several branch or secondary carriers, by which latter such loaded pallet boards are carried to suitable places of deposit.

My improved transfer mechanism is arranged to operate automatically, to pick up in succession the loaded pallet boards (or other parcels) from the main or primary carrier, and to deposit the same smoothly and accurately upon the branch or secondary carrier.

In the accompanying drawings which illustrate the invention, like characters indicate like parts throughout the several views. Referring to the drawings: Figure 1 is a plan view illustrating my improved transfer mechanism operatively applied to a carrier system such as above indicated, some parts thereof being broken away and some parts being shown in section. Fig. 2 is a vertical section taken on the line

$x^2 x^2$ of Fig. 1. Fig. 3 is a vertical section taken on the line $x^3 x^3$ of Fig. 1. Fig. 4 is a transverse vertical section taken on the line $x^4 x^4$ of Fig. 1. Fig. 5 is a detail in vertical section taken on the line $x^5 x^5$ of Fig. 1. Fig. 6 is a transverse vertical section taken on the line $x^6 x^6$ of Fig. 5. Fig. 7 is a detail in section taken on the line $x^7 x^7$ of Fig. 5. Fig. 8 is a detail in section taken on the line $x^8 x^8$ of Fig. 5. Fig. 9 is a detail view partly in plan and partly in horizontal section, showing a so-called coupling shaft for operating the so-called parcel lifter of the transfer mechanism, and showing also certain associated parts. Fig. 10 is a fragmentary view in elevation showing one end of the coupling shaft illustrated in detail in Fig. 9. Fig. 11 is a detail in section taken approximately on the line $x^{11} x^{11}$ of Fig. 2; Fig. 12 is a diagrammatic plan view illustrating the arrangement of a carrier system of the general character above indicated, wherein several branch or secondary carriers are employed in connection with a main or primary carrier.

Of the parts of the carrier system proper, the numeral 1 illustrates an elongated frame work of the so-called main carrier and the numeral 2 indicates the laterally spaced endless carrier belts which as shown, are in the form of cables, and are arranged to run over laterally spaced pairs of grooved wheels 3 and 4 secured respectively to shafts 5 and 6 journaled in the sides of the frame work 1. The branch or secondary carriers, each comprises a pair of laterally spaced endless belts or cables 7 arranged to run over grooved wheels 8 and over other grooved wheels not shown. All of the wheels 8 are secured on a long shaft 9 that extends parallel to the main carrier at one side thereof, is journaled in suitable bearings 10 and 11, and is geared to the shaft 5 by a pair of miter gears 12. On the said shaft 9 is a pulley 13 over which the power driven belt 14 runs to impart motion to two shafts 5 and 9, and hence to the main and branch carriers.

For picking the pallet board or other parcel up off from the belts 2 of the main carrier, I provide a so-called parcel lifter which is mounted on a small rectangular supplemental frame, preferably made up of side frames 15 that are spaced apart and tied together by pipe sections or sleeves 16. This supplemental frame is detachably secured to

bearing plates 17 secured on the sides of the main carrier frame 1. This detachable connection between the said supplemental frame and the said bearing plates 17, is conveniently made by rods 18 that are passed through sleeves 16 and through the said bearing plates 15 and 17. A pair of parallel rock shafts 19 and 20 are journaled upon ends in the sides 15 of the detachable supplemental frame, and these rock shafts are provided with laterally spaced pairs of parallel arms 21 that are connected by parallel lifting bars 22. Also as shown, said rock shafts 19 and 20 are provided with depending arms 23 that are connected by a link 24. A pair of laterally spaced grooved guide wheels 25 are loosely journaled on the rock shaft 19 and serves to support the upper portions of the belts 2, so that the parcel or loaded pallet board will not sag the belts at the point where it is carried above the lifting bearings 22. Mounted in depending portions 15^a of the bearing plates 15 of the detachable supplemental frame, is a third rock shaft 26, to which is secured a pair of laterally spaced trip arms 27, the free upper ends of which extend above the upper portions of the belts 2 in a position to be engaged by the pallet board or other parcel. The said pallet board in the drawings is indicated by the letter *a*, and the bricks contained thereon are indicated by the letter *b*.

To one of the trip arms 27, a coiled spring 28 and a trip rod 29 are attached at one end. The other end of said spring is loosely attached to the rock shaft 19, and the other end of said trip rod 29 is connected to one arm of the bell crank 30 that is intermediately pivoted to a bearing 31, secured on one of the fixed sleeves 16 of the detachable supplemental frame.

Nearly transversely opposite to the so-called parcel lifting device above described, the long shaft 9 is provided with fixed longitudinally spaced collars 32, and between these collars, located adjacent thereto, said shaft is provided with loose bearing sleeves 33, see Figs. 1, 5 and 6, that are grooved at their sides and tops so as to receive and detachably hold U shaped or bifurcated bearing heads 34 of a detachable bearing yoke 35. The intermediate portion of this yoke 35 has a bearing 36, in which is journaled the hub of the miter gear 37 that meshes with a miter gear 38 loosely journaled on the shaft 9. At its extended end, the hub with the gear 37, carries a crank arm 39.

Between the hub of the gear 38 and the adjacent bearing sleeve 33, the cam hub 40 is loosely mounted on shaft 9, and is provided with a radially projecting arm 41 and with a lateral projecting segmental cam 42, which latter, at its highest point, terminates abruptly, as best shown in Figs. 5 and 8, the hub of the said gear 38 being recessed to

afford a clearance for the said cam 42. As shown in Figs. 5 and 6, the bearing sleeves 33 are provided with upwardly projecting dowel pins 33^a that engage seats in the bifurcated heads 34 and assist in holding same in working position, and permitting the latter to be lifted from working position when it is desired to detach the bearing yoke 35 and parts mounted thereon. The said bearing yoke 35 is provided with a depending pedestal 43, which is made up of two overlapped sections rigidly but detachably connected by a bolt and slot connection 44, shown in Fig. 2. The lower end of this pedestal 43 is detachably connected by a pin 45 to a bearing 46 on the floor or ground support.

The beveled gear 38 is provided with clutch teeth that engage with similar clutch teeth 47 formed on one end of a clutch sleeve 48, which latter is slidably mounted on the shaft 9, but caused to rotate therewith by means of a key 49. A light coiled spring 50 on shaft 9 is compressed between the clutch sleeve 48 and the adjacent bearing sleeve 33, and exerts a force which tends to engage the clutch teeth of said sleeve 48 and gear 38. A clutch releasing pin 51 is slidably mounted in the hub of the gear 38, one end in position to be engaged by the segmental cam 42 of the cam hub, and with its other end in position to engage the end of the clutch sleeve 48 inward of its clutch teeth 47, as best shown in Figs. 5, 7 and 8. A rod 52 is connected at one end to the above crank 30, and at its other end, is detachably connected by a pin 53 to the arm 41 of the cam hub 40.

Rigidly secured to the floor adjacent to the shaft 9, and about transversely opposite to the central portions of the lifting bearings 22, is a pedestal 54, to the upper end portion 105 of which, is rigidly secured a U shaped coupling yoke 55. The downturned end of a detachable bearing bracket 56 is engaged between the yoke 55 and the pedestal 54, and is securely held thereby by means of friction and gravity.

Rotatively mounted in the detachable bearing 56 and loosely seated at its lower end in the base of the pedestal 54, is an upright oscillatory shaft or stem 57, the upper end of which, as shown, is turned into a horizontal position to afford a carrying arm 58. Below the bearing 56, the shaft 57 is provided with a radially projecting hub 59, to which a short headed arm 60 is swiveled. The crank rod 61 is pivotally connected at one end to the crank 39 of the gear 37, and at its other end, it has a downturned stem and is pivotally mounted in the head of the short swiveled arm 60 of the vertical rock shaft 57. This crank rod 61 is preferably made of two overlapping sections that are adjustably connected by a bolt and slot connection 62. Near its crank connected end, the crank rod 61 is provided with a laterally projecting cam pin 130

63 preferably equipped with the roller, which under upward movement of the crank 39, is adapted to engage an arm 64 secured to the intermediate portion of an extension rock shaft 65. This extension rock shaft 65, at its outer end is journaled in a bearing 35^a on the yoke 35, and at its inner end it is flattened at 65^a and fits a correspondingly formed seat in the adjacent end of the rock shaft 19, so that the said shaft 65 constitutes a detachable portion of the said shaft 19. A coiled spring 66 on the shaft 65 reacts against the bearing 35^a and against the hub of the arm 64, and yieldingly holds the said shaft 65 coupled to the rock shaft 19.

10 A lever like parcel transferring frame 67 shown as provided with a bifurcated outer end portion, is swiveled or rotatively mounted on a horizontal projecting portion 58 of the vertical rock shaft or stem 54. To the inner end portion of this transferring frame 67, is secured a segmental cam 68 that extends concentric to the axis of the vertical rock shaft 57 and rests upon a supporting 20 roller 69, shown as journaled to a small bracket 70, (see Figs. 1, 4 and 11). The segmental cam 68 has an abruptly inclined intermediate portion 68^a, and furthermore, the free end portion thereof, is slightly inclined 25 for an important purpose which will appear in the description of the operation.

Operation: The directions in which the endless carrier belts 2 and 7 are driven, are indicated by arrows marked adjacent thereto on Fig. 1. When the loaded pallet board is placed on the carrier belt 2, it will be carried toward the left in respect to Fig. 1, and toward the right in respect to Fig. 3, until it strikes the upper ends of the tripping 30 arms 27, whereupon this engagement, will, through the rods 29 and 52, and an intermediate bell crank 30, rock the cam hub 40 far enough to cause the shouldered extremity of the cam 42, to be out of engagement with 35 the pin 51, thereby permitting the spring 50 to move the constantly driven clutch sleeve 48 toward the left in respect to Figs. 1 and 5, thus coupling the miter gear 38 to the driving shaft 9. This causes the driving 40 shaft 9, through the miter gears 37 and 38, to rotate the crank 39. The upward movement of the said crank 39 causes the roller 63 to engage the arm 64 and thereby rock the sectional shaft 19—65, and thus to raise 45 the two lifting bars 22 and cause the latter to pick up and elevate the pallet board. This same movement of the crank 39, acting through the connecting rod 61, carries the transferring frame 67 from its normal position indicated by the full lines in Fig. 1, into the receiving position indicated by the dotted lines in Fig. 1. When the said transferring frame is thus moved from its normal into its receiving position, the roller 69, 50 acting first on the cam portion 68^a, and then

on the tail portion of the said cam, raises the free end of the said transferring frame and guides the same slightly under the loaded pallet board, which at a time when the said transferring frame reaches its said dotted line receiving position, is elevated or held upward by the lifting bars 22, which then stand in a position indicated by the dotted lines in Fig. 3. While the lifting bars 22 and the transferring frame are in the relative position above stated, the crank 39 approaches the limit of its movement toward the right in respect to Fig. 1, and toward the left in respect to Fig. 2, and the roller 63 then passes out of engagement with 55 the free end of the arm 64 and thus permits the bars 22 to drop, leaving the lower pallet board deposited upon the transferring frame 67.

The return movement of the lower half 60 stroke of the crank 39, serves to return the transferring frame 67 to its normal position over the receiving position of the belts 7; and just before the said transferring frame reaches its normal position, the abruptly 65 inclined portion 68^a of the cam 68, runs over the supporting roller 69, thereby causing the free end of the said transferring frame to lower and thereby deposit the lower pallet board on the said belt 7 in a position at 70 a right angle thereto.

When the crank 39 completes its full 75 stroke, the pin 51 reaches the highest point on the cam 42 of the cam hub 40, (which latter assumed its normal position when the 80 lifting bars 22 carried the pallet board upward out of engagement with the free ends of the spring retracted tripping arms 27) and thereby forces the clutch sleeve out of 85 engagement with the clutch teeth of the gear 38. This of course, disconnects the gear 38 from the driving shaft 9, and leaves 90 all of the parts of the transferring mechanism in their normal positions. By the pin 95 51, cam 42, and clutch members, it will be seen that they constitute a one-revolution 100 clutch mechanism for throwing the crank 39 into and out of action.

By reference to Fig. 12, it will be noted 105 that several branch or secondary carriers are employed in connection with the main or primary carrier. When it is desired to shift the transferring mechanism from the position for co-action with one of the branch carriers, into a position for delivery to another of the said branch carriers, the rock shaft extension 65 should first be uncoupled 110 by an entire movement from the rock shaft 16. Then, by withdrawing the rods 18, and removing the pin 53 from the cam hub arm 115 41, all of that part of the transfer mechanism which is applied to the side frames 1, and of the main carrier, may be detached 120 therefrom, and when brought into another proper position, the location may be again 125 130

coupled thereto by reapplying the said rods 18 and inserting the said pin 53 in the arm 41, since the collars 32, grooved bearing sleeves 50, gear 38 and clutch sleeve 48, are 5 permanently applied on the driving shaft 9 adjacent to each of the several branch or secondary carriers.

The bearing yoke 35, together with the gear 37, the crank 39, the crank rod 61, the 10 vertical rock shaft 57, the transferring frame 67, and connected parts, may be detached and removed, this operation simply requiring that the pin 45 in the floor bearing 46, be first removed, and then the 15 bifurcated heads 34 be lifted from the grooved bearing sleeves 33, and the bearing 56 be lifted out of the yoke 55.

To provide for the application of the detachable parts just noted, the floor bearing 20 46 and pedestal 54 with yoke 55, should also, of course, be provided at the several places where they are to be applied for co-operation with the several branch carriers. The pedestal 43 is made vertically adjustable so 25 that it may be adapted to irregularities in the floor. The crank rod 61 is made adjustable so that the movements of the transferring frame 67 may be properly regulated in respect to the lifting movements of the 30 lifting bars 22.

From what has above been said, it is thought to be evident, that a highly efficient transfer mechanism for carrier systems of the general character above stated, has been 35 provided. By making most of the parts of the transferring mechanism detachable and capable of operative connection at different points along the main carrier, a very great saving in cost is effected. The efficiency of 40 the mechanism above described, has been demonstrated in actual practice.

What I claim is:

1. The combination with a primary carrier and a secondary carrier extending at an 45 angle thereto, of an oscillatory parcel transferring frame, a driving shaft, a one revolution clutch intermittently driven from said shaft, a crank connection for oscillating said transferring frame from said clutch, and a 50 clutch trip arranged to be engaged by parcels on said primary carrier.

2. The combination with a primary carrier and a secondary carrier extending at an angle thereto, of a parcel transferring mechanism, comprising an oscillatory parcel transferring frame, a drive for oscillating

said frame, including the one revolution clutch, a clutch trip adapted to be engaged by parcels on said primary carrier, and means for lowering said transferring frame 60 when the same is moved into position to deliver to said secondary carrier, and for raising the same when moved from said position toward a position in which it is adapted to receive parcels from said primary carrier. 65

3. The combination with a primary carrier and a secondary carrier extending at an angle thereto, of a parcel transfer mechanism, comprising an oscillatory parcel transferring frame, a parcel lifting device in connection with said primary carrier, an intermittent drive for oscillating said transferring frame and for actuating said parcel lifting device, and a trip for said drive, arranged to be engaged by parcels on said primary carrier. 70 75

4. The combination with a primary carrier and a secondary carrier extending at an angle thereto, of a parcel transfer mechanism, comprising an oscillatory parcel transferring frame, a parcel lifting device in connection with said primary carrier, a drive including a one revolution clutch for oscillating said transferring frame and for actuating said parcel lifting device, a clutch 80 trip arranged to be engaged by parcels on said primary carrier, and a device for lowering said transfer arm when in a position to deliver to said secondary carrier. 85

5. The combination with a primary carrier and a multiplicity of secondary carriers extending at an angle thereto, of a parcel transfer mechanism, comprising an oscillatory parcel transferring frame, a parcel lifting device in connection with said primary carrier, a drive for oscillating said transferring frame and for actuating said lifting device, and including a one revolution clutch mechanism and a clutch tripping mechanism, and which transferring frame, 90 parcel lifting device, and clutch tripping mechanism, are detachable and adapted for delivery of parcels to any one of said secondary carriers, the said clutch mechanism being permanently applied in connection with 95 each of said secondary carriers. 100 105

In testimony whereof I affix my signature in presence of two witnesses.

WILLIAM AAB.
